MECHANICAL CALENDAR

Carl E. Tally, Cleburne, Tex., assignor of one-half to John E. Rosenbalm, Cleburne, Tex.

Application February 2, 1939, Serial No. 254,277

2 Claims. (Cl. 40—113)

This invention relates to mechanical calendars and has for an object to provide a device of this character which may be easily manipulated to indicate any desired date in a present, past or future year.

A further object is to provide a mechanical calendar of simplified construction, which will include essentially a manually operable dial and a face plate, the former being provided with 10 seven calendars, each beginning with a different day of the week and adapted to be selectively displayed through an opening in a face plate, the face plate having printed on the outer surface seven tables containing even hundreds of 15 years; intermediate years, and the months arranged in their cyclical order and used in conjunction with the calendar months on the dial to find any desired date.

With the above and other objects in view the 20 invention consists of certain novel details of construction and combinations of parts hereinafter fully described and claimed, it being understood that various modifications may be resorted to within the scope of the appended claims without 25 departing from the spirit or sacrificing any of the advantages of the invention.

In the accompanying drawings forming part of this specification,

Figure 1 is a front elevation of a mechanical 30 calendar constructed in accordance with the invention, with parts broken away.

Figure 2 is a top plan view of the calendar shown in Figure 1.

Figure 3 is a rear elevation of the calendar 35 with portions broken away.

Figure 4 is an end elevation of the calendar.

Figure 5 is a detail longitudinal sectional view taken on the line 5—5 of Figure 3.

Figure 6 is a detail longitudinal sectional view 40 taken on the line 6—6 of Figure 3.

Figure 7 is a detail longitudinal sectional view taken on the line 7—7 of Figure 3.

Figure 8 is a detail sectional view taken on the line 8—8 of Figure 3.

45 Referring now to the drawings in which like characters of reference designate similar parts in the various views, 10 designates a face plate which is substantially rectangular in contour. The face plate is formed near the upper corners 50 thereof with vertically disposed narrow openings 11 and 12, which respectively expose slides 13 and 14 indicative of months and years. In the upper central portion of the face plate a relatively large rectangular opening 15 is formed through 55 which a selected one of seven calendars 16 may

be exposed, these calendars being printed on a dial 28, best shown in Figure 3.

The face plate is formed with an opening 18 adjacent to and below its central portion, in which is disposed a bolt 19. Mounted on the 5 bolt, adjacent the head thereof is a washer 26 overlapping a bracket 20. Beneath this washer is a smaller washer 9 slightly thicker than, and disposed within an opening in the bracket. The smaller washer 9 forms a bearing for the bracket. 10 The bracket and the smaller washer lie flat on the face plate 10. This smaller washer permits the bolt to be tight yet permits the bracket to be movable. The bracket 20 is provided with apertured ears 21 adapted to receive oppositely disposed hinge lugs 22 formed on an operating handle 23.

A substantially arcuate portion of the face plate is cut away concentrically with the bolt aperture to provide an opening 24, best shown in 20 Figure 1, a relatively narrow tongue 25 of the face plate projecting upwardly into the opening to mount the bolt. Below the face plate there is mounted on the bolt a relatively thick spacing washer 21, and below the washer is mounted another small washer 8 forming a bearing within an axial opening in the dial 28 and permitting the bolt to be tight yet permitting the dial to be loose to be revolved. The dial 28 has printed or otherwise formed thereon the seven monthly 25 calendars 16 before referred to.

Each calendar begins with a different day of the week and is adapted to be selectively displayed through the large opening 15 in the face plate. The calendars 16 are arranged tangentially on the dial, concentric with the bolt. 30

Exposed through the arcuate opening 24 in the face plate are radially disposed slots 31 numbered one to seven consecutively in a counter clockwise direction beginning at the upper left portion of the dial, each slot being formed in the dial adjacent a respective calendar 16, as best shown in Figure 1. The slots are adapted to be selectively engaged by a depending lug 32 carried by the handle. A knob 33 is secured to 40 the handle for manipulating the handle to selectively dispose the lug in the slots as will presently be described.

The peripheral edge of the dial is provided with a plurality of notches 34 adapted to be engaged by a spring pawl 35 which is fixed at one end to the rear face of the face plate. The pawl releasably holds the dial in position with one of the calendars 16 exposed through the opening 15.

Printed, or otherwise formed on the front sur- 55

face of the face plate are seven tables 36, each table being arranged diametrically opposite a respective slot in the dial and being numbered consecutively in a counterclockwise direction, 5 from one to seven beginning with the lowermost table on the right side of the face plate as best shown in Figure 1. These tables display even hundreds of years, intermediate years, and the months arranged in their cyclical order, leap 10 years being designated by four dots arranged as a border around the number of the year.

The beforementioned slide 13, displaying the names or abbreviations of months, is slidably mounted in a guide bracket 38, best shown in 15 Figure 8, having opposed guide loops 39 to receive the angularly bent longitudinal edges 40 of the slide. The slide may be manually manipulated to display the name or abbreviation of any desired month through the narrow elongated opening 11.

There are four of the slides 14 each displaying numerals from 1 through 9 to zero, as best shown in Figure 1. As best shown in Figure 6, these slides are mounted in guide brackets 41 formed 25 preferably from a single sheet of material deformed to provide opposed loops 42 which receive the angularly directed longitudinal edge portions 43 of the slides. The slides may be manually manipulated to display the numerals of any desired year, as best shown in Figure 1.

As before stated, each of the calendars 16 begin on a different day of the week and each display 31 days. In order to conceal some or all of the numerals from 29 to 31 inclusive when a calendar 35 is being used to designate a particular month having less than 31 days, a slide 44 is provided with an angularly directed struck up guide loop 45, best shown in Figure 7, which receives a guide flange 46 struck up from the face plate. The opening 47 in the face plate from 40 which the guide flange is removed receives a tab 48, best shown in Figure 1, through the medium of which the slide may be moved transversely of the face plate. The slide is provided with stepped portions 49 and 50 adapted to mask undesired numerals on the calendar when the slide is manipulated by manual movement of the tab 48.

In the operation of the device first present the calendar 1 through the opening 15. Thus the dial is placed in its initial position. The handle 23 is then moved over the slot opposite the table 36 containing the desired even hundreds of years, which in the present example would be slot number 2 corresponding to the table number 2 containing the year 1900. The lug 32 is then engaged 55 in the slot whereupon the handle is swung clockwise to the right until the handle engages the end wall 51 of the opening 24. Then the lug 32 on the handle is withdrawn and the handle is then moved to the slot opposite the table containing the desired intermediate year, for example 38, and this will be slot number 6 opposite table number 6. The handle is now depressed to engage the lug in this slot and the handle is thereupon swung again to the right until it engages the end wall 51 of the opening 24. This operation 60 is repeated as to the desired month, and results in the exhibition in the opening 15 of the desired

month of that particular year, in the present embodiment the month of October of the year 1938. If the date being sought is in a leap year, and the date is after February 29, the slot number 2, corresponding to the leap year table number 2 is used, to bring the proper month into display, the slot receiving the lug of the handle and the handle being swung to the right clockwise until movement is stopped by contact with the end wall 51 of the opening 24, as previously 10 described.

From the above description it is thought that the construction and operation of the invention will be fully understood without further explanation.

What is claimed is:

1. A mechanical calendar comprising, a face plate, a dial rotatably mounted on the face plate, there being seven monthly calendars displayed on the dial concentric with the axis of the dial, each 20 calendar beginning with a different day of the week, there being a sight opening in the face plate through which the calendars are selectively exposed, there being tables displayed on the face plate containing even hundreds of years, intermediate years, and months arranged in their cyclical order, there being an arcuate opening 25 formed in the face plate concentric with the axis of the dial and terminating in stop walls, there being slots formed in the dial opposite respective 30 calendars, and an operating lever swivelled on the face plate at the axis of the dial having a projection adapted to be selectively engaged in the slots to turn the dial until the handle engages one of said stop walls for exposing a determinable 35 calendar through said sight opening.

2. A mechanical calendar comprising a face plate formed with relatively narrow openings adjacent its upper edge, slides back of the face plate bearing tables indicating months and years respectively to be exposed selectively through said openings, there being a sight opening formed in the face plate below and between said first named openings, the face plate being formed with an arcuate opening below said sight opening, a bolt disposed axially in the face plate with respect to said arcuate opening, a bracket on the bolt having hinge ears, a handle having hinge lugs engaged in said ears, a dial fixed to the bolt and spaced from the rear face of the face plate, there being seven monthly calendars displayed on the dial, each calendar beginning with a different day of the week and adapted to be selectively displayed through said sight opening, there being radially disposed slots formed in the dial adjacent respective calendars and exposed through said arcuate opening, a lug formed on said handle adapted to be engaged in said slots, the edges of the dial being provided with notches adjacent respective calendars, and a spring carried by the face plate releasably and interchangeable in said notches, there being formed on the outer surface of the face plate seven tables, said tables being arranged opposite the slots in the dial, said tables containing even hundreds of years, intermediate years and the months arranged in their cyclical order.

CARL E. TALLY.
